UNITED STATES PATENT OFFICE.

PAUL H. SCHULZ AND CHRISTIAN JESSEN, OF MILWAUKEE, WISCONSIN.

DESIGN FOR A SIGNAL HEAD.

Application filed December 20, 1921. Serial No. 523,780. Term of patent 3½ years.

To all whom it may concern:

Be it known that we, PAUL H. SCHULZ and CHRISTIAN JESSEN, citizens of the United States, residing at Milwaukee, in the county of Milwaukee and State of Wisconsin, have invented a new, original, and ornamental Design for Signal Head, of which the following is a specification, reference being had to the accompanying drawing, forming part thereof.

Figure 1 is a top plan view of our signal-head design, and

Figure 2 is a side elevation of the same.
We claim:

The ornamental design for a signal-head, as shown.

In testimony that we claim the foregoing we have hereunto set our hands at Milwaukee, in the county of Milwaukee and State of Wisconsin.

PAUL H. SCHULZ.
CHRISTIAN JESSEN.
